UNITED STATES PATENT OFFICE.

JOHN OVERALL, OF DRUMMOYNE, NEAR SYDNEY, NEW SOUTH WALES, AUSTRALIA.

APPARATUS FOR CLEANING SHIPS' BOTTOMS.

Application filed November 28, 1922. Serial No. 603,781.

To all whom it may concern:

Be it known that I, JOHN OVERALL, a subject of Great Britain, residing at St. George's Crescent, Drummoyne, near Sydney, in the State of New South Wales, Commonwealth of Australia, have invented new and useful Improvements in Apparatus for Cleaning Ships' Bottoms, of which the following is a specification.

This invention relates to apparatus for cleaning ships' bottoms whereby the operation is carried out whilst the ship is water-borne, thereby obviating the necessity of dry docking her for the purpose.

Referring to the accompanying sheets of explanatory drawings—

Fig. 1 is a diagrammatical view of the side elevation of a ship to which the invention is shown applied;

Fig. 2 is a similar plan view, and

Fig. 3 a transverse section of the vessel.

Fig. 4 is a perspective view of the reciprocating gear for operating the working rope.

Fig. 5 a plan view of the bow and stern boom upon which is mounted the traversing gear of the working rope fair-leads.

Fig. 6 is a perspective view showing the scraper device together with means for varying the vertical position of the working rope.

Fig. 7 is a longitudinal section of the scraper device.

Fig. 8 is a top plan thereof.

13 represents the ship's hull and 14 is the working rope to which the scrapers 15 are attached by means of the clamps 16 and bridles 17. The working rope 14 is rove through the pulleys 18 slidably attached by the sleeves 19 to the booms 20, the latter being secured on the bow and stern of the ship 13 by suitable clamps or such like devices 21 and at the ends secured by stays 22 attached to the hull of the ship. The free ends 23 of the working rope 14 are secured to and wound round barrels 24 rotatably operated by power appliances and provided with ratchet locking mechanism 25. These barrels are journalled upon a bed plate 26 adapted to slidably move between

guides 27 on the rocker arm 28. This latter is journalled at 29 on a foundation 30 on a punt 31 secured to the ship, or it may be mounted upon the ship itself. 31^a is the engine for operating the reciprocating gear. 32 is a connecting rod journalled at the lower end of the rocker arm 28 and adapted by its

operation to cause the said rocker arm to oscillate. Upon the upper end of the said rocker arm are journalled a pair of pulleys 33 over which the working rope is lead. 34 is a belt driven pulley adapted through its shaft, to which it is keyed, to cause the grooved disc 35 to revolve and to frictionally engage, when required, with either one or other of the correspondingly grooved discs 36 on the barrels 24. This mechanism is provided to enable the hauling rope 14 to be wound on to either of the aforesaid barrels as required. The engagement of the grooved discs 36 with the driving disc 35 is obtained by causing the bed plate 26 to slide in horizontal plane as required, within the guides 27. This movement is obtained by operating the lever 37, journalled at 38 on the rocking arm 28 and mechanically attached to the bed plate 26 by the pin 39. By the to-and-fro movement of the lever 37, either grooved disc 36 is caused to engage separately with the driving grooved disc 35. The operating handles 40 are employed, if need be, to draw in "slack" should it occur in the rope 14.

The scrapers 15 are each preferably formed of four members secured together by shackles 41 which permit of ample freedom of play of such members, enabling them, at all times, to lie close to the surface of the hull 13, when in operation. The scraper blades 42 are secured to a frame 43 shaped preferably to form a truncated cone at each end of the device. The forward end 44 of each scraper blade 42 is sloped downwards to enable it to ride over obstructions such as the lap of a plate, when in operation. 45 are runners, the rubbing faces of which are raised slightly above the level of the scraper blades 42 to prevent the latter from coming into contact with the paint on the ship's hull and so injuring it. These runners are tapered downwards as at 46 where they approach the scraper blades 42. For clearness of illustration the centrally placed runners are not shown in Fig. 6. 47 are brushes adapted to remove the material loosened by the scraper blades 42. The scraper 15 is attached to the working rope 14 by means of the shackles 16 and bridles 17. These shackles are so constructed that they may be coupled and uncoupled readily to permit of the positioning of the scraping apparatus on the working rope 14, with facility. The frames 43 are constructed of some buoyant material to ensure that the scraper blades 42 are kept up to

the surface of the hull when at work by such buoyant property, and 48 are floats employed to impart greater buoyancy when such is required.

- 5 The sleeves 19 are adapted to be slidably moved along the booms 20 by means of the controlling lines 49 rove through the pulleys 50 thus enabling the load of the working rope 14 to be altered in horizontal plane at will.
- 10 The guide blocks 51 are interposed at suitable distances apart and through these the working rope 14 is roved. These guide blocks 51 are adapted to be secured by vertically disposed guy ropes 52 to the vessel 13 and by 15 them they are raised and lowered to hold the working rope 14 in the required horizontal position when in operation.

In carrying out the invention the working rope 14 is operated by some source of power positioned either on a floating structure secured to the side of the vessel to be cleaned, or it may be mounted upon the deck of the vessel itself. In the drawings it is shown positioned upon a punt secured along 25 side the vessel. The rope 14 is roved through the several fair-lead pulleys as illustrated and described and is reciprocated to make the scrapers 15, attached thereto, move in a to-and-fro direction over a definite portion 30 of the hull, in horizontal plane. Upon the completion of the operation on a given portion of the hull, one or other of the barrels 24 is rotated by means of the gear described, or by some other suitable apparatus, 35 to wind in a length of working rope 14 corresponding to the length of the travel pre-arranged for the operation of the scrapers 15. The corresponding barrel automatically unwinds a similar length of its coiled rope. 40 Upon this operation being completed the ratchet mechanism 25 secures the barrels 24 in position. Reciprocating motion is again imparted to the working rope 14 until a fresh portion of the ship's surface has been 45 cleaned. The operation above described is repeated until the whole of the surface in the "run" of the rope is cleaned. The latter is then moved in vertical plane to take up a fresh working position. This is done by 50 hauling on, or slackening up, the lines 52 controlling the guide blocks 51. By this means the working rope 14 is moved either up or down in relation to the hull as required, and so a fresh working "run" is provided for it. In making these adjustments the fair-lead pulleys 18 on the sliding collars

19 on the booms 20 are adjusted to ensure that the working rope operates in correct line, accurate adjustment being readily obtained by means of the lines 49.

In operation, I may attach one or more scrapers to the working rope, depending on the working conditions or on the condition of the foulness of the hull.

By these means the scraper or brush 61 is guided to traverse the required surface at will.

I claim:—

1. Apparatus for cleansing ships' bottoms comprising a working rope, scraping devices attached to such rope, means for imparting reciprocating motion to the said rope, means for adjusting its working position both in horizontal and vertical plane in relation to the hull of the vessel, and means for advancing or retiring the position of the scrapers relative to the cleaned portion of the hull of the vessel, as the work proceeds.

2. Apparatus for the purpose specified comprising a working rope to which a scraping device is attached, means for imparting reciprocating motion to such rope, means for winding-in either end of the rope to advance or retire it and the scraping device attached thereto as the work proceeds, and means for altering the position of the rope both in horizontal and vertical plane to cause the scraping device to traverse the surface of the hull during the operation.

3. In apparatus as described means for imparting a reciprocating motion to the working rope consisting of winding barrels and a journaled member oscillated by suitable power, a pair of fair-lead pulleys situated at one end of the member over which the working rope is lead to the barrels, a bed plate at the other end of the member upon which the working rope barrels and friction gear are journaled, such bed plate being adapted to be slidably moved at will in horizontal plane within its guides to cause either of the friction pulleys to engage individually with a driving friction pulley to wind in the working rope as required.

In testimony hereof I affix my signature in presence of two witnesses.

JOHN OVERALL.
